Henry Smith

UNITED STATES PATENT OFFICE.

HENRY SMITH, OF COLLEGE POINT, NEW YORK.

INK-WELL.

1,308,817.

Specification of Letters Patent.

Patented July 8, 1919.

Application filed May 15, 1918. Serial No. 234,817.

To all whom it may concern:

Be it known that I, HENRY SMITH, a citizen of the United States, residing at College Point, in the county of Queens and State of New York, have invented certain new and useful Improvements in Ink-Well, of which the following is a specification.

This invention relates to improvements in bottles or containers for writing fluids and 10 has for its object to provide means whereby the fluid may be held in the neck of the bottle.

Another object of the invention is to provide in an ink bottle means whereby the 15 writing fluid may be supplied to a pen without the necessity of having to project the pen into the body of the bottle.

A still further object of the invention is to provide in the neck of an ink bottle an ink 20 containing cup having a valve closed bottom and means whereby a free passage of the fluid is provided between the cup and body of the bottle.

With the above and other objects in view, 25 I have invented the device illustrated in the accompanying drawings in which—

Figure 1 is a sectional view of my improved writing fluid container.

Fig. 2 is a similar view showing a different 30 position thereof.

Fig. 3 is a detail elevational view of an ink cup and feeding tube.

Fig. 4 is a detail perspective view of an 35 ink cup.

Fig. 5 is a section on line A—A Fig. 1.

Fig. 6 is an end view of a tube member.

Like reference characters indicate like 40 parts throughout the following specification and in the several views in the drawings in which 1 is an ink bottle or other container

having a neck 2 seated in which is an ink cup 3 having a tubular extension 4 forming a seat for the cup. The cup has a tapering bottom 5 terminating in an opening 6 forming 45 a seat 7 for the ball valve 8. A perforated disk 9 or other suitable means may be used for holding the ball 8 adjacent its seat 7. The tube 4 is provided with openings 10 at its bottom edge and similar openings 11

50 near its upper end to permit free inflow of ink in the body portion 12 of the bottle. The upper edge 13 of the cup 3 terminates short of the mouth 14 of the bottle to accommodate the stopper pad 15 seated in the 55 screw cap 16 of the bottle. Longitudinal grooves 17 are provided in the outer surface

of the wall 18 of cup 3 to permit ink to enter the body 3 for the overflow of cup 3 when filling the bottle. The bottle may be filled originally before the ink cup is inserted 60 in the neck of the bottle, or before the ball valve and its retainer are put into place. The bottom of the cup 3 has a reduced portion 19 which seats in the reduced opening 20 in the upper end of tube 4. 65

By screwing down the cap 16 and turning up the bottle as in Fig. 2 ink will flow into the cup 3 through the opening 6 as the ball valve is unseated and as the bottle is again righted the ball will take its seat and close 70 the opening 6 and retain the cup 3 full of ink whereby the ink may be used without having to run the pen handle down into the bottle and getting ink thereon which ordinarily would be transferred to the fingers 75 and hands of the writer.

Having now described my invention that which I claim to be new and desire to procure by Letters Patent is:

1. In a bottle a stopper, a cup in the neck 80 of said bottle and a tube under the cup forming a support therefor, an opening in said cup and a ball valve normally closing said opening, said cup having passages along its outer wall surface extending into 85 said bottle.

2. In an ink bottle having a neck and a stopper therefor, a cup in said neck, passages between the cup and side wall of said neck, said passages permitting free passage 90 of air or liquid from the cup to the interior of the bottle, and a seat for supporting the cup, said seat consisting of a tube and extending to the bottom of the bottle and a valve normally closing an ink passage in 95 said cup.

3. In an ink bottle having a neck, a cup in said neck, passages between the cup and side wall of said neck, said passages permitting free passage of air or liquid from the 100 cup to the interior of the bottle, a seat for supporting the cup, said seat consisting of a tube, and extending to the bottom of the bottle, a stopper adapted to be pressed against the edge of said cup. 105

4. In an ink bottle having a neck, a cup in said neck, passages between the cup and side wall of said neck, said passages permitting free passage of air or liquid from the cup to the interior of the bottle, a seat 110 for supporting the cup, said seat consisting of a tube, and extending to the bottom of

the bottle, a stopper adapted to be pressed against the edge of said cup, a cap in which the stopper is seated, said cup having an opening in its bottom, and a ball valve for closing the opening.

5. In an ink bottle having a neck, a cup in said neck, passages between the cup and side wall of said neck, said passages permitting free passage of air or liquid from the cup to the interior of the bottle, a seat for supporting the cup, said seat consisting of a tube, and extending to the bottom of the bottle, a stopper adapted to be pressed against the edge of said cup, a cap in which the stopper is seated, said cup having an opening in its bottom, a ball valve for closing the opening, and means for holding the ball adjacent said opening.
10. In an ink bottle having a neck, a cup in said neck, passages between the cup and
15. In an ink bottle having a neck, a cup in said neck, passages between the cup and

side wall of said neck, said passages permitting free passage of air or liquid from the cup to the interior of the bottle, a seat for supporting the cup, said seat consisting of a tube, and extending to the bottom of the bottle, a stopper adapted to be pressed against the edge of said cup, a cap in which the stopper is seated, said cup having an opening in its bottom, a valve for closing the opening, said valve being a ball, and means for holding the ball adjacent said opening, said means consisting of a perforated disk seated in the cup adjacent the opening.

20. In an ink bottle having a neck, a cup in said neck, passages between the cup and

25. In an ink bottle having a neck, a cup in said neck, passages between the cup and

30. In an ink bottle having a neck, a cup in said neck, passages between the cup and

In testimony whereof I affix my signature 35 in the presence of two witnesses.

HENRY SMITH.
